UNITED STATES PATENT OFFICE.

ELMER A. SATTLER, OF BELLEVILLE, ILLINOIS, ASSIGNOR TO BELLEVILLE STOVE & RANGE COMPANY, OF BELLEVILLE, ILLINOIS, A CORPORATION OF ILLINOIS.

DESIGN FOR A STOVE.

Application filed November 11, 1927. Serial No. 24,077. Term of patent 7 years.

To all whom it may concern:

Be it known that I, ELMER A. SATTLER, a citizen of the United States of America, residing at the city of Belleville, county of St. Clair, State of Illinois, have invented a new, original, and ornamental Design for a Stove, of which the following is a specification, reference being had to the accompanying drawing, forming a part thereof.

The drawing is a perspective view of a stove embodying my new design.

I claim:

The ornamental design for a stove, as shown.

ELMER A. SATTLER
